DRIER

James P. Martel, Evanston, Ill., assignor to Oliver
United Filters Incorporated, San Francisco,
Calif., a corporation of Nevada

Application July 1, 1935, Serial No. 29,276

5 Claims. (Cl. 34—12)

This invention relates to driers and in particular to a continuous drier wherein the material to be dried is carried on an endless support and during the course of the drying operation is turned over by means of a rabbling device.

In general the object of my invention is the provision of a drying chamber through which a bed of discrete particles to be dried is passed, and which is provided with a plurality of spaced discs which serve to turn over the particles forming the bed, and thereby present new surfaces to the drying medium.

More specifically the object of the invention is the provision of a rabbling device comprising two sets of discs mounted on a shaft, the members of each set being parallel and disposed intermediate the members of the other set, the discs of one set being disposed at an angle with respect to the discs of the other set.

The invention possesses other advantageous features, some of which with the foregoing, will be set forth at length in the following description where that form of the invention which has been selected for illustration in the drawings accompanying and forming a part of the present specification is outlined in full. In said drawings, one form of the invention is shown, but it is to be understood that it is not limited to such form, since the invention as set forth in the claims may be embodied in a plurality of forms.

Referring to the drawings:

Figure 1 is a diagrammatic side elevation of an endless drier embodying the objects of my invention.

Figure 2 is a section taken on the line 2—2 of Fig. 1.

Figure 3 is an enlarged end elevation of one form of rabbling device shown in its operative position with respect to an endless carrier or support.

Figure 4 is an end elevation showing a modification of the rabbling device as shown in Figure 3.

Figure 5 is an end elevation of still another modified form of rabbling device.

Referring particularly to Figure 1, my invention contemplates a drying chamber 1 supported by vertical frame members 2, and provided with air intakes 3, and air outlets 4. Passing through the heating chamber 1 and dividing it into upper and lower compartments is an endless conveyor 5 comprising a plurality of pallets 6, having foraminous bottoms as clearly shown in Fig. 2. The pallets are provided with flanged wheels 7 adapted to travel on a track formed by a pair of

spaced guide rails 8, supported by the vertical frame members 2 and by additional superstructure as indicated in Figure 1. The material to be dried is fed in a wet condition to the endless conveyor 5 by means of a hopper 9, supported above the endless conveyor by means of suitable superstructure. Secured to the superstructure at the opposite end of the drier is a hopper 11 into which the dried material is discharged. Mounted intermediate the ends of the upper compartment 10 of the heating chamber 1 and between the lateral walls 12 of the chamber, is a shaft 13. This shaft may be conveniently journaled in bearings 14 carried by the lateral walls 12, and is designed to be driven by means of a pulley 15 secured to one of its ends and which in turn may be driven by means of a motor 16 carried by the superstructure of the device as shown in Figure 1. Since the drier per se including the endless conveyor and pallet construction is well known to the industry the details of its construction need not be given.

As shown in Figure 3 the shaft 13 has been provided with two sets of spaced discs. The discs 17 constituting the members of one set are each perpendicular with the shaft 13, while the discs 18 constituting the members of the other set are all parallel with one another, but are disposed at an angle of substantially 80° with respect to the shaft 13. It is to be noted that the discs 18 lie intermediate the discs 17.

In Figure 4 two sets of discs have again been shown. The discs 19 constituting the members of one set lie intermediate the discs 21 constituting the members of the other set, and the discs of both sets are disposed at an angle of substantially 80° to the shaft 13 but at opposite pitches.

In the modification shown in Figure 5 the discs 22 and 23 are secured to the shaft 13 at right angles thereto, while the discs 24 are all parallel with each other and are secured to the shaft 13 at an angle of substantially 80° thereto.

In the operation of the device the wet or moist material to be dried, such as for example, coal, is fed to the endless conveyor 5 by means of the hopper 9. During its passage through the drying chamber 1 it is subjected to the drying action of hot air entering the chamber by means of the intakes 3 and passing downwardly through the material to be dried and then out through the outlets 4. During the passage of the material beneath the rabbling device the discs cut through the bed of material with the result that the individual particles forming the bed are

turned over and thereby expose new surfaces to the action of the air passing through the bed.

As the result of actual tests made with this type of equipment, it has been found that the arrangement of discs as shown in Figure 4 is preferable to the arrangement shown in Figure 3, and that the arrangement shown in Figure 3 is preferable to the arrangement shown in Figure 5. In the arrangement shown in Figure 4 the particles forming the bed of material are turned over without crushing the individual particles and without forcing them into and injuring the supporting screen. In the arrangement shown in Figure 3 there is inclined to be a slight crushing of the particles and in the arrangement shown in Figure 5 this action is even more pronounced, although in both of the latter modifications there is no tendency to force the material into the supporting screen.

20 I claim:

1. In a drier comprising a traveling support adapted to carry a bed of material: a rotatable shaft mounted above said support; discs mounted on said shaft at an angle therewith; the shaft and discs being so disposed with respect to the support that the lower peripheries of the discs will rotate through the material carried by the support as the material passes beneath the discs; and means for positively driving said shaft.
2. In a drier comprising a traveling support adapted to carry a bed of material: a rotatable shaft mounted above said support; discs mounted on said shaft at an angle with said support, the shaft and discs being so disposed with respect to the support that the lower peripheries of the discs will rotate through the material carried by the support as the material passes beneath the discs; and means for positively driving said shaft.
3. In a drier comprising a traveling support adapted to carry a bed of material: a rotatable shaft mounted above said support; two sets of spaced discs mounted on said shaft in such a

manner that the discs of each set are parallel and lie intermediate the discs of the other set and that the discs of one set make an angle with the discs of the other set, the shaft and discs being so disposed with respect to the support that the lower peripheries of the discs will rotate through the material carried by the support as the material passes beneath the discs; and means for positively driving said shaft.

4. A drier comprising a substantially sealed chamber; a foraminous support arranged to travel through and divide said chamber into upper and lower compartments; an air intake communicating with one of said compartments and an air outlet with the other; a shaft disposed within said upper compartment parallel to the foraminous support; discs mounted on said shaft at an angle thereto, the shaft and discs being so disposed with respect to the support that the lower peripheries of the discs will rotate 20 through the material carried by the support as the material passes beneath the discs; and means for positively driving said shaft.

5. A drier comprising a substantially air tight chamber; a foraminous support arranged to 25 travel through and divide said chamber into upper and lower compartments; an air intake communicating with one of said compartments and an air outlet with the other of said compartments; a shaft disposed within said upper 30 compartment parallel to the foraminous support; two sets of spaced discs mounted on said shaft in such a manner that the discs of each set are parallel and lie intermediate the discs of the other set and that the discs of one set make 35 an angle with the discs of the other set, the shaft and discs being so disposed with respect to the support that the lower peripheries of the discs will rotate through the material carried by the support as the material passes beneath the 40 discs.

JAMES P. MARTEL.
